(57) **CLAIM**

The ornamental design for a trailer hitch receiver assembly with towing accessory ports, as shown and described.

DESCRIPTION

FIG. 1 is a perspective view of the trailer hitch receiver assembly with towing accessory ports of the present invention;

FIG. 2 is a front elevational view thereof;

FIG. 3 is a rear elevational view thereof;

FIG. 4 is a right side elevational view, the left side elevational view being a substantial mirror image thereof;

FIG. 5 is a top plan view thereof; and,

FIG. 6 is a bottom plan view thereof.
